ROTARY, STRAIGHT-PULL JAR ASSEMBLY

Donald U. Shaffer, Pico, Calif.

Application June 25, 1937, Serial No. 150,289

17 Claims.

(Cl. 255—27)

This invention is a rotary-stem, straight-pull release jar assembly for various operations in deep well drilling practice.

In deep well work the lower portion of a string of tool sections may become so lodged in the formation or in a cemented casing in the well hole, or so jammed from one cause or another that it cannot be rotated free or pulled without undue and hazardous strain on the string of parts to 10 the well head, and to the head works.

It is known that up-jarring shocks are highly effective in efforts to release the stuck part, or "fish" as the case may be.

An object of this invention is to provide a 15 simple, practical, reliable and readily operative means whereby to accomplish the upjar blow without necessity of rotating the tool string in either direction to effect the actual shock vibration to the stuck part.

20 A further object of the invention is to provide a novel jar assembly in which the function of jarring is accomplished by the application of a suitable degree of tension to the free section of the tool string whereby to overcome resistance of a variable re-action device which controls 25 interconnection between coordinate elements of the mechanism.

An additional object is to provide a jar mechanism in which means are provided to accomplish 30 rotation of the jarring assembly in either a closed or an open position of the parts, and also to provide for rotation of one section, as a hammer section, as to another section, say a mandrel unit, for variation or adjustment of the resistance of 35 the said re-action device.

A still further object is to provide a tool string jar assembly in which the jar controls are adapted to be both set for action and to be tripped for jar 40 impingement by a simple reciprocative movement of the upper, tension-applying section of the assembly.

Particularly, an object is to provide a jar assembly in which the several parts of the control means are of simple, rugged and low-cost structure and are capable of ready assembly and interchange, and may severally be stored and transported to facilitate emergency field renewals. In other words an object is to eliminate costly and cumbersome elements, in jars of the class here concerned, and which are subjected to severe 50 stresses during service.

The invention consists in certain advancements in the art of well tool string jars as set forth in the ensuing disclosure and having, with the above, additional objects and advantages as hereinafter developed, and whose construction, combination and details of means, and the manner of operation thereof will be made manifest in the following description of the annexed illustrative embodiment of apparatus; it being under-

stood that modifications, variations and adaptations may be resorted to within the scope, principle and spirit of the invention as it is more directly claimed in the appendage.

Figure 1 is an axial, sectional elevation of the 5 jar assembly with the parts in closed, load-applying and rotating relation, and with the jarring hammer in open or spaced relation as to its anvil. Figure 2 is a side elevation of the assembly wash-pipe, per se. Figure 3 is a cross-section on line 10 3—3, Fig. 1, through the hammer. Figure 4 is a cross-section on line 4—4, Fig. 1, at the head of assembly latching means or connectors. Figure 5 is a sectional elevation of a connector bolster part or collar. Figure 6 is a cross-section on line 6—6, 15 Fig. 1, through the assembly mandrel and an adjusting sleeve. Fig. 7 is a cross-section on line 7—7 of Fig. 1, and Figure 8 is a sectional elevation of the adjusting sleeve. Figure 9 is an elevational, axial section of the hammer in striking 20 juxtaposition to its anvil.

At the jar assembly bottom there is a pin 2 for screwing onto any desired combination of parts therebelow in the usual manner, say of a fishing tool. The pin has internal threads 3 to receive 25 the threaded end of a mandrel shank 4 having an enlarged body or piston 5 packed and slidably and turnably in a shell or barrel part 6.

The barrel 6 has its lower end provided with 30 clutch spurs 7 to interlock with pin body spurs 2^a when the barrel is in the lower, illustrated position whereby to load and rotate the subjacent parts of the tool string, as may be required in fishing or other operations. The foot of the barrel 6 has interior, clutch lugs 8 to move upwardly 35 into interlock with respective lugs 9 on the lower end of the piston body 5 of the mandrel 4.

The mandrel 4 is hollow for circulation of drilling fluid and has a stem 4', above the piston 5, attached at 10 to the lower end of a wash-pipe 11 40 which extends to the top of the assembly, Fig. 1. The mandrel stem is provided with suitable spline means or keys 12 to slidably and non-turnably receive a sleeve or nut 13, above the piston 5, threaded at 14 into an elongated shell or jacket 45 part 15 which threads at 16 into the barrel 6. Parts 2, 4 and 11 form a mandrel structure or section of the assembly.

When the barrel 6 is lifted free at clutch 7 from the pin 2 the barrel may be rotated about 50 the mandrel 4—4' with the result that the stationary or fish-held, splined stem 4' holds the sleeve 13 from rotating with the attached jacket 15 and barrel, with the result that the sleeve 13 will climb on the mandrel, if the jacket is turned 55 right-hand, as here intended. This action is for the purpose of placing a suitable, helical spring 17 under increased compression between its anti-friction seat ring 18 on the crown 19 of the sleeve 13 and an upper bolster or wedge-collar 20 which 60

slides freely on the wash-pipe 11, and in shell part 15.

The spring 17 is encased by the shell jacket 15 whose upper end screws at 21 into a shell thimble 5 22 attaching at its upper end to a bushing anvil 23.

The wedge of the bolster collar 20 faces upward and forms a seat for the toe ends 24' of a plurality of wholly independent, link-forming, rigid latch elements 24 of arcuate cross-section 10 and having external shoulders 25 at their foot ends to upwardly engage a hard shoe-ring 26 which is set in the jacket 15 just below the thimble 22; the spring supported bolster collar 20 normally thrusting the latch shoulders 25 15 outward into such interlock with the shoe-ring 26.

In this position of the parts the upper hook ends 24' of the latch elements 24, which surround the adjacent pipe 11, are interlocked into 20 the neck recess 27 in the lower end of a cylindrical hammer 28 having a piston body 29 and, being splined at 30 in the relative bore of the bushing anvil 23, below which the hammer piston is packed and reciprocates in the nipple or 25 shell part 22, when permitted. The hammer 28 screws at 31 into the near end of a string coupling box 32 in which the wash-pipe 11 is slidably packed at 33.

The parts 28 and 32 form the hammer section 30 of the assembly, and parts 23, 22, 15 and 6 form the anvil section.

Regarding the pin 2 and its mandrel 4-4' as a standing part of the tool string and as attached to a subjacent string or fishing tool, a tension placed on the box 32 will be taken by hammer 28 and from it by the coupling means here consisting of the linking latches 24 which are interlocked by the wedge collar 20 against and under the shell ring 26 of the jacket 15. 35 40 This therefore takes the tension and pulls up the barrel 6 and unclutches it from the jaws 2' of the pin 2.

Now by right-handing turning of the related string parts 32, 28, 22, 15 and 6 as to the standing 45 mandrel 4, the sleeve nut 13 will screw upward at 14 in the jacket 15 and will compress the spring to the desired degree.

In order to obtain a jarring impingement of the now spaced hammer piston 29 against the 50 superjacent end of the anvil 23, string tension is applied to the box 32 and to the hammer 28 to a sufficient degree to crowd the toe ends of the linking latches 24 inwardly from the shoe-ring 26 to clear the latch shoulders 25 therefrom. The inward pressure and movement of the latch toe ends 24' overcomes the up-thrust of the spring 17 on the bolster collar 20, and as the shoulders 25 of the latches ultimately pass 55 into the shoe ring 26 the released hammer snaps up, by reason of the tension in the string length thereabove, and the shoulder 28' of the piston 29 of the hammer sharply bounds against the near end of the anvil 23, Fig. 9. The percussive shock is transmitted by the connected shell parts 60 65 70 75 22, 15, 16, 5, 4 and 2 to the tool attached therebelow.

The coupling, latch means 24 travel with the hammer 28 by reason of the interlock at 27, this being of such nature to allow the lower end of the latches to swing in or out on the bolster device 20.

The jarring action may be repeated at will at intervals times only by the period needed to again lower the mandrel 28 and, by the latches 75 24, repress the yieldable bolster 20 to again set

the latch toes 24' under the shoe ring 26. The tool is then ready for a repeat jar. Both the setting and the tripping action of the coupling means, here the latches 24, are accomplished by only straight up or down motions of the hammer section of the tool string, thereby eliminating hazard of reverse turn, unscrewing of the threaded string sections at any joint. 5

The hammer string may be pulled up to un-clutch the parts 7-2' to unload the standing pin 10 2 and then rotated free to turn the jacket 15 to adjust the pressure of the spring 17 of the bolster device, or the hammer may be pulled high enough to close the clutch parts 8-9 to enable the pin 2 to be rotated without load or be pulled 15 from the hole, with the fish if this has been jarred loose, or without it.

What is claimed is:

1. A well string jar assembly including: a hammer section and a relatively telescopic anvil section to be jarred thereby and a mandrel section, having means to engage a fish held in a well hole, on which the anvil section is telescopic between limits, a coupling means for tensionally connecting the hammer and the anvil sections in hammer spaced relation, and a yieldable bolster device slidably combined with the mandrel and releasably holding said connecting means in effective position and adapted to release the coupling means under a predetermined tension, 20 and permit spring of the hammer to its anvil and thereby jar the connected mandrel. 25

2. A jar assembly for well strings, including a mandrel section, having means to engage a fish, and hammer and anvil sections relatively splined 30 together and the anvil section sliding on the mandrel, a coupling device connecting the hammer and the anvil sections in open hammer relation for co-reciprocation on the said mandrel, and a yieldable bolster device having a part axially adjustable on the mandrel and having a spring for 35 setting the coupling device to connect the hammer and the anvil sections and adapted to release the coupling under predetermined tension thereon between the hammer section and the 40 anvil section to permit jar action and means operative by rotation of the anvil section to adjust the spring. 45

3. A jar assembly for well strings, including a mandrel having means to connect to a fish held 50 in a hole, connective, splined and telescopic hammer and anvil sections having opposed strike faces, a collapsible coupler carried by one of said sections and releaseably interlockable with the other in spaced hammer relation, the coupled 55 sections having limited sliding connection with the mandrel, means for co-rotatively connecting the anvil to the mandrel, and a yieldable bolster mounted in one of the sections and operative against the coupler to expand it to interlock said 60 sections until overcome by a predetermined tension between the sections. 65

4. A jar assembly for well strings, including a hammer section and an anvil section slidably splined thereon and each provided with strike 70 faces for jar action, a collapsible coupler for connecting the sections in open hammer relation and being attached to one section for travel there-with, a mandrel having means for attaching to a fish on which the connected sections have limited 75 sliding motion and are rotatable, means to turnably interlock the said section to the mandrel at either of stroke ends, a collar to engage and set the coupler in connecting position, and a yieldable support in one of the sections for the collar 75

to move it to coupler setting position and for permitting the collar to yield and allow disconnection of the coupler under given tension between the said sections.

5. A jar assembly as set forth in claim 4, and said support having means operative by rotation of said sections for varying the reaction pressure of the said support.

6. A well string jar assembly having slidably 10 splined hammer and anvil sections with opposed striking faces, a mandrel on which one of said sections is slidable and turnable and having means to rotatively interlock therewith and limit sliding motion, coupler means carried by one of the sections and collapsibly interlockable with the other in open hammer position thereof, and an axially adjustable bolster device for engaging and expansively setting the coupler in effective position and a spring yieldably supporting the bolster for 20 automatic release of the connected sections under given tension and permit a snap action of the hammer to the anvil for jarring.

7. A well jar assembly as set forth in claim 6, and including means operative by the rotation of 25 said sections operatively connected to the mandrel and to one of said sections whereby to readily adjust the degree of bolster resistance by said spring to the string tension and thereby the jar force.

8. A well string jar assembly including a hammer structure and an anvil section slidably splined thereto and having a strike face therefor, a coupler attached to the hammer and having collapsible engagement with the anvil section to hold it 35 open as to the hammer, a mandrel structure on which the anvil section is slidably and turnably attached and having stop means for rotational interlock therewith, an axially slidable bolster in the anvil section to expand the coupler to section 40 connecting position, and a spring yieldably supporting said bolster so that it will automatically release the coupling and disconnect the hammer structure, for jarring impingement on the anvil, under predetermined string tension on the 45 coupler.

9. A jar assembly as set forth in claim 8, and including an adjustable seat for the spring and which is axially shiftable by and upon relative rotation of the hammer and the anvil as to the 50 mandrel; said seat being axially shiftable on the mandrel.

10. A well string jar assembly including a hammer and a set of relatively free latch elements attached thereto and reciprocative thereby, an anvil section telescoped on the hammer and strikable thereby, yieldable bolster means for expanding the latches into interlock with the anvil section to connect the hammer thereto in spaced relation and whereby to automatically release the hammer 55 under predetermined tension for rebound against the anvil, and means operative by rotation of the anvil section to vary the release resistance of the bolster.

11. A jar assembly as set forth in claim 10, and including a mandrel structure, and the bolster means including a wedge collar slidable, on the said structure, under a straight down stroke of the hammer to effect a setting of the said elements.

12. A well string jar assembly including a rotary hammer section, an anvil section slidably

splined thereon for co-rotation, said section having mutual striking faces, an axially shiftable wedge collar and a supporting spring therefor in the anvil section, a coupler controlled and engaged by said collar for tensionally connecting the 5 hammer and the anvil sections in open hammer relation, a mandrel, and means axially movable on the mandrel and carrying, and regulating the resistance of, the spring and being shiftable by rotation of the hammer and the anvil sections; 10 said 'coupler being operative on the collar to automatically repress it so as to release the hammer from the anvil at a predetermined tension on the coupler.

13. A well string jar assembly as set forth in 15 claim 12, and in which the collar is repressible by inward movement of the coupler to effect automatic resetting of the coupler in section connecting relation.

14. A well string jar assembly including slidably splined, co-rotative hammer and anvil sections having mutual strike faces, a coupler including independent, expansible latch parts for tensionally and releaseably interlocking the sections in open hammer relation, an axially yieldable bolster means engaging the coupler and holding it in expanded connecting position, and control means including an axially shiftable support for the bolster and which is axially operative by rotation of said sections to vary the resistance of the bolster means on the coupler. 30

15. A well string jar assembly including co-rotative, relatively slidable hammer and anvil sections, a set of link forming latches each independently, pivotally connected to and reciprocative by 35 one of said sections, a yieldable bolster including a wedge collar to expand the latches and a spring having an axially adjustable support screwed in the other section, and seating means in one section and against which the toes of the latches are 40 expanded to connect the sections by reaction of the bolster and which seating means is operative under given tension on the latches to contract the latches and release the connection of the sections for rebound of the hammer under tension to jar 45 the anvil section.

16. A well jar assembly including the combination as set forth in claim 15, and having means to non-rotatively hold said support while its section is rotated for varying the position of the said seating means and determine the releasing tension of the interlocked hammer and anvil sections, and thereby regulate the jar blow while the assembly is in fish attaching position in a well hole. 50

17. A well string jar assembly including a hammer section having a set of coupling elements pivotally suspended therefrom and reciprocative thereby and therewith, an anvil section splined on the hammer section and strikable thereby, axially slidable bolster means for expanding the pivoted latches into attachment with the anvil section to connect the hammer in open position to the anvil, a spring for supporting the bolster, and means operative by rotation of the anvil to vary the reaction of the spring on the 60 bolster; said bolster automatically releasing the coupling elements under a strain according to the spring resistance and said bolster acting on a down stroke of the coupling elements to re-set the attachment. 65
